CONCEALED WASTE RECEPTACLE

Original Filed March 9, 1925

UNITED STATES PATENT OFFICE

WILLIAM F. ROBERTS, OF NASHVILLE, TENNESSEE

CONCEALED WASTE RECEPTACLE

Original application filed March 9, 1925, Serial No. 14,188. Divided and this application filed February 9, 1927. Serial No. 166,970.

This case is a division of Roberts, Serial Number 14,188, filed March 9, 1925, for concealed waste receptacles.

The object of this invention is to provide a strong easily operating guide means for drawers and like receptacles.

Other objects and advantages of the invention will be apparent from the following description, considered in conjunction with the accompanying drawings, in which

Figure 1 is a perspective view showing a waste receptacle embodying the invention applied to the bottom of a desk.

Figure 2 is a longitudinal vertical section through the waste receptacle, certain of the elements removably supporting the receptacle being shown in side elevation.

Figure 3 is a transverse vertical section through the waste receptacle and through the supporting means therefor.

Figure 4 is a perspective group view showing a fragmentary portion of the waste receptacle together with co-operative elements for anti-frictionally supporting the waste receptacle for sliding movement.

In the accompanying drawings, particular reference being had to Figure 1, 2 indicates the parallel sidewalls of a drawer or receptacle, made of fibre, wood, metal, or the like. Slide bars 10 are attached to the sides 2 of the receptacle body, preferably by rivets therethrough. Each slidebar is substantially angular in cross sectional contour, and comprises an arm 8 secured by screws 9 or

like fastening devices, to the upper edge portion of one of the sides 2 and a horizontal arm 10 which extends outwardly from said sides, preferably in the plane of the upper edge of the latter. The arms 10 of each of the slide bars preferably has a depending lip or bead 11 at its outer edge. In carrying out the invention, I provide means removably supporting the receptacle on the desk bottom between the lower drawer 15 so that the end member 4 will be at the outer end of the receptacle. The supporting means for the receptacle comprises a pair of rails 17 each of which is substantially U-shaped in cross sectional contour. However, one of the arms 50 of each of the rails 17 is wider than the other

arm of the rail and is formed with an outwardly extending lateral attaching flange 18 at its edge. The attaching flange 18 is substantially parallel to the web portion of the rail and the web portions of such rails, therefore will be horizontal when the attaching flanges 18 are secured against the under side of the bottom rail 13 of the desk by screws 19 or like fastening devices. A plurality of rollers 20 are rotatably supported between the side flanges of each of the rails as by means of axial shafts 21 extending transversely of the rails and having the end portions thereof extended through aligned openings 22 in the said flanges of the rails.

From the foregoing description of the various parts of the device, the operation thereof may be readily understood. The receptacle body is arranged to permit the horizontal flanges 10 of the slide members 8-10 to rest upon the rollers with the depending bead 11 disposed between the rollers 20 and the adjacent side flanges of the supporting rails and with the end member 4 at the outer end of the receptacle body. The end member 4 may be provided with a handle 23. During the operation of the drawer, the weight of same is carried on the rollers 20, which in turn are carried by the axial shafts 21 and the channel bars 17, the weight of the drawer will serve to rotate the rollers when the drawer is operated horizontally, thereby providing a rolling contact with minimum friction. The receptacle body may be entirely removed from the supporting means by pulling it outwardly clear of the guides. Other applications of the invention may be made as will be apparent to those skilled in the art.

I claim:—

In combination a pair of horizontally disposed parallel rails, a channel member extending longitudinally of the under face of each rail and having lateral attaching flanges attached to the rails, rollers supported in the channel members for rotation about horizontal axes and disposed directly beneath the rails, a drawer arranged for longitudinal movement between the channel members, angle rails secured to the upper edges of the side walls of the drawer and having their

horizontal flanges located between the under face of the rails and the rollers, and a downwardly extending flange formed on the horizontal flanges of the angle members and lying between the rollers and one side wall of each channel member to retain the drawer against lateral shifting.

WILLIAM F. ROBERTS.
